INVENTOR:

Charles Brooke Jones.

By: Ed. Steel Jackson
Attorney.

UNITED STATES PATENT OFFICE.

CHARLES BROOKE JONES, OF ABOVE CYNWYD, PENNSYLVANIA.

RESISTANCE-SWITCH.

1,395,579.

Specification of Letters Patent.

Patented Nov. 1, 1921.

Application filed January 16, 1920. Serial No. 351,856.

To all whom it may concern:

Be it known that I, CHARLES BROOKE JONES, a citizen of the United States, residing above Cynwyd, on Old Ford Road, 5 in the county of Montgomery and State of Pennsylvania, have invented a certain new and useful Resistance-Switch, of which the following is a specification.

My invention relates to switch boxes and 10 switches making a number of contacts corresponding to differing switch connections and disconnections.

The purpose of my invention is to provide for reducing the illumination from a 15 light by including a resistance within the circuit by which the light is controlled, the resistance being placed within the switch element, usually a switch box.

A further purpose is to make a wall switch 20 box which can be connected with a light, requiring no special outside wiring or connections but providing for inserting resistance within the light circuit.

A further purpose is to seat resistance 25 elements within the body of a switch block or casing flush or otherwise, and whether of plunger form or rotating.

Further purposes will appear in the specification and in the claims.

30 I have preferred to illustrate my invention by but one form, selecting a form which is practical, efficient, reliable and inexpensive, and which at the same time well illustrates the principles of my invention.

35 Figure 1 is a central vertical section through a switch embodying the preferred form of my invention.

Fig. 2 is a section of Fig. 1 upon lines 2—2.

Fig. 3 is a section of Fig. 1 upon line 3—3.

40 Fig. 4 is a broken side elevation of a rotary switch contact member shown in Fig. 1.

Fig. 5 is a sectional perspective showing the switch contact element seen in Fig. 4.

45 Fig. 6 is a perspective view of the fixed contact of the switch with diagrammatic connections.

Figs. 7—10 are diagrammatic views illustrating the invention.

In the specification similar numerals indicate like parts.

Though devices for reducing the voltage which is effective upon lamps for the purpose of dimming them have been well known for years, these have required special lamp 55 sockets or special outside connections or other features individual to the lamp or

circuit as distinguished from connections self contained by the switch itself. It is my purpose to make these functions available by switch construction so that the outside 60 connections, including the lamp sockets, may be unchanged and yet all of the advantages may be available that can be secured by the use of the special lamp sockets or special circuit connections indicated. 65

Though I recognize that my invention is applicable to any switch which is provided with more than two contact positions, whether adapted to be operated by a plunger or by a rotary button, I have preferred to apply 70 my invention, by way of illustration merely, to a form of wall switch which has the advantage of both, in that it is a plunger operated and yet has a rotary contact member. The form of switch block and switch to 75 which this is applied and shown in the illustration is generally old, but the contacts indicated and the inclusion of resistance within the switch block so as to be included in the circuit when certain contacts are made, 80 are believed by me to be new.

Taking up the general form of switch shown, the block or body 11 is ordinarily of porcelain and is intended to lie within and be held by the wall and to be covered 85 by a protective and decorative plate cover, not shown. It is recessed at 12 to provide a space for the switch contacts, both fixed and movable. Openings 13 permit insertion of the outside connections 14, 15. 90

Within the recess I place fixed contacts 16, 17, 18, 19 suitably provided with binding screws 20 or other fixed or temporary connecting devices. The fixed contacts are preferably in the form of spring blades to 95 engage on opposite sides of movable knife blade contact members of which the highest is 21, the lowest 23 and three at the same intermediate height are shown at 22, 22', 22''. These are all electrically connected and are 100 carried by a plug 24 which is rotated by any suitable mechanism, whether of rotary button or plunger form. The end 25 of the plug is seated in and steadied by the walls of a recess 26 in the box. 105

In the illustration rotation is secured by a plunger 27 guided by a cross head 28 and depending rods 29. The pins are carried by a plate 30 held in position by screws 31. The plunger is movable over a rotary drum 110 32 having spiral or cam path 33 in which a plunger pin (not shown) rides to turn the

drum with downward movement of the plunger. The lower end of the drum is connected through a snap action, not new to me, with a ratchet wheel 34 engaged by the pawl 35, held to its duty by a spring 36, so that each movement of the plunger and corresponding partial turning of the drum in a clock-wise action (looking downwardly) will carry the pawl with it and will, therefore turn sleeve 34 (upon which the pawl is mounted) with it. This turns plug 24 a quarter turn each time. This corresponds to the several contact positions for the switch illustrated.

15 The binding screws and contact fingers of the several fixed contacts are mounted upon suitable standards or supports which need no description and these are held in position in the bottom of a box by means 20 well known in the art and not shown.

Between fixed contact 17, which forms one terminal of the switch and fixed contact 19, is connected a resistance shown as may be in two parts, 38 and 39, in order to form 25 a point 40 of intermediate connection with fixed contact 18.

Four fixed contacts are used as compared with three, for example, in order to make it possible to insert two different resistances 30 which can be applied in series to give a maximum dimming effect and of which one part only is used to secure partial dimming in another switch position, whereas the use of three fixed contacts alone would normally 35 provide but one extent of dimming corresponding to one resistance inserted.

With the construction shown, forming one arrangement only among the many which may be used to secure the contacts desired, 40 the fixed contact 18 is the highest, corresponding in height to that of movable contact 21; fixed contact 16 is next in height, corresponding in height to all three movable contacts 22, 22' and 22"; and fixed contacts 45 17 and 19 are the lowest in position, and correspond in height to movable contact 23.

With the movable contact inserted within the fixed contacts in the angular position shown in Figs. 5 and 6, (shown diagrammatically in Fig. 7) movable contact 21 will lie above fixed contact 16 without engagement therewith, and the switch will be in open position since the connection is open at this, one of the terminal contacts. 50 Though it is not therefore material, it might be noted that movable contacts 22 and 22" lie above the fixed contacts 17 and 19, and that movable contacts 22' and 23 both lie below the fixed contact 18; so that 55 the switch is open at all of the contacts.

Turning the movable switch in a clockwise direction (looking downwardly) to the position shown diagrammatically in Fig. 8, it will be seen that the highest movable contact 60 65 21 will now lie above and will not engage

with the fixed contact 17, connection being open at this point. The movable contact 22" will lie under fixed contact 18 without engagement with it, the connections being therefore open also at this point. However, movable contact 23 will engage with fixed contact 19 and movable contact 22" will engage with fixed contact 16 forming a direct connection across the movable element between the two terminal contacts 16 and 19 70 and rendering the full voltage available upon the outside circuit. This does not include 75 artificial resistance.

Turning the movable contact member another quarter turn in a clockwise direction 80 (looking downwardly), the movable contact 21 will now engage with the fixed contact 18. The movable contact 22 will lie above terminal contact 19 without making connection with it. The movable contact 22' 85 will engage with the terminal contact 16 and the movable contact 22" will lie above and will not engage with the fixed contact 17. Though the terminal 19 is not engaged, a circuit will be made through the terminal 90 16 across the movable contact member to contact 18, through resistance 39 to the fixed contact terminal and out to the line, connecting the circuit with part of the resistance 95 —39— in circuit.

Turning the movable contact element another quarter turn in the same counter clockwise direction (looking downwardly) the movable contact 21 will lie above and will not engage with the fixed contact 19, the 100 circuit being open at this point. The movable contact 22 will engage with fixed contact 16 closing this (one) terminal. The movable contact 23 will engage with the fixed contact 17, closing the circuit at this 105 point, and the movable contact 22" will lie under and therefore will not be engaged with the fixed contact 18. Though connection will not be made at fixed contact 19, the circuit will be closed through the terminal contact 16; the movable contact element, fixed contact 17 and the two resistances 38 and 39 to the fixed contact terminal at 19, introducing a maximum of resistance in the circuit. 110

The two different switch resistance points 115 have been selected by way of illustration, and it will be evident that a simplified form with but a single resistance included would mean merely dropping of the contacts 21 and 18, if an intermediate (open) position 120 be desired, without altering the position of the other contacts; and dropping these two contacts and spacing the others by 120° if but one open position of a switch be desired.

It will be evident that the same principles are applicable to any other form of switch having more than two positions whereby discriminating contacts can be made and in which resistance can be carried to render the 130

different contacts effective for the purpose intended. Though these may differ in form and appearance and attain but a part of the benefit of my invention, I purpose covering 5 all such herein as come within the spirit and scope of my invention.

What I claim as new and desire to secure by Letters Patent is:—

1. A switch comprising a plurality of fixed 10 contacts, two of them having their contact surfaces at the same height and spaced by two having their contact surfaces at heights different from these two and from each other, a resistance within the switch connected with the two contacts of equal height, one of them being a terminal and at an intermediate point with one of the contacts of different height, which is not a terminal, in combination with a plurality of interconnected 15 movable contacts, three at a height corresponding to one of the fixed contacts of unequal height and two corresponding to the contacts of equal height and the other fixed contact respectively, whereby the terminal 20 fixed contacts may be connected without any of the resistance, with part of the resistance only or with all of the resistance in the circuit as desired.

2. A switch comprising fixed contact members 25 in quadrant position of which two adjoining members are terminals, a resistance connected from one of the terminals to the contact directly across therefrom and at an intermediate position connecting with an intermediate contact which is not a terminal, in combination with a movable contact member 30 having interconnected contacts adapted to open the switch or to engage with the terminal free from resistance connection and any of the other three terminals in turn to open the switch or to include none of the resistance or differing resistance at will.

3. A switch comprising a plurality of fixed 35 contacts, quadrant spaced having two opposite contacts, one a terminal, at the same height and the intermediate two contacts, including the second terminal, at heights different from the first two and from each other and resistance connection between the first terminal and the contact of equal height 40 opposite it and connected at an intermediate

point to the intermediate non-terminal contact in combination with a rotary contact member having interconnected fingers in quadrant position, three adapted to engage 55 the second terminal, one at the fourth quadrant position adapted to engage the fixed contact connected with the intermediate resistance position and a fifth contact across the axis from said fourth contact and adapted 60 to engage with the two contacts of equal height.

4. In a device of the character stated, a switch-body having a recess, fixed switch contacts located within the recess, two of them being terminals, a resistance within the switch body connected to two of the fixed contacts, one of the contacts being a switch terminal, and at an intermediate point to a third switch contact and a movable contact 70 member adapted to engage any of the 3 switch contacts in turn and connect it with a fourth switch contact comprising the other terminal of the switch.

5. In a device of the character stated, a 75 switch body having a recess, fixed switch contacts located within the recess, two of them being terminals, a plunger switch operating member, and a rotary switch contact member and connections operated by the 80 plunger to rotate the same to connect one of the switch contacts with any of the other switch contacts in turn and to open the switch, in combination with a resistance within the switch body connected between 85 a terminal fixed switch contact and one of the other fixed contacts.

6. In a device of the character stated, a switch body having a recess, fixed switch contacts located within the recess, two of 90 them being terminals, a plunger switch operating member, and a rotary switch-closing contact member and connections operated by the plunger to rotate the same to connect one of the switch contacts with any of the 95 other switch contacts in turn and to open the switch, in combination with a resistance in the switch body, connected between two of the contacts and a connection from an intermediate point in said resistance to a third 100 contact.

CHARLES BROOKE JONES.
